BRASSIÈRE

Joseph R. Bowen, Los Angeles, Calif., assignor to
Hollywood-Maxwell Co., Los Angeles, Calif., a
corporation of California

Application July 14, 1944, Serial No. 544,885

1 Claim. (Cl. 2—42)

1

This invention relates to brassières.

In garments of this character, two breast receiving cups are provided for supporting the breasts. A body-encircling band to which the cups are appropriately fastened serves to hold the garment in place. This band is often supplemented by shoulder straps.

Brassières of this character are entirely satisfactory; but, when low-cut evening gowns are worn, such gowns reveal that part of the brassière which extends between the cups. It is one of the objects of this invention to provide a brassière that can be worn under such gowns without exposing any part of the brassière.

In order to accomplish this result, the material connecting the breast cups at the hollow between the breasts is disposed well below the rounded portions of the breasts; and the cups are otherwise supported so that they are maintained in proper position with respect to the breasts. Accordingly it is another object of this invention to provide a cup supporting means that may be left concealed even when low-cut gowns are used.

This invention possesses many other advantages, and has other objects which may be made more clearly apparent from a consideration of one embodiment of the invention. For this purpose there is shown a form in the drawings accompanying and forming part of the present specification. The form will now be described in detail, illustrating the general principles of the invention; but it is to be understood that this detailed description is not to be taken in a limiting sense, since the scope of this invention is best defined by the appended claim.

Referring to the drawings:

Figure 1 is an elevation of a brassière embodying the invention;

Figs. 2 and 3 are enlarged sectional views, taken along correspondingly numbered planes of Fig. 1; and

Fig. 4 is a pictorial view showing a brassière in position on a wearer.

The brassière is shown as provided with the two breast cups 1 and 2 that are domed to accommodate the breasts of the wearer. These cups may be made of any suitable fabric, such as lace, silk, or a combination of fabrics.

The lower edges of the cups 1 and 2 form a line which is a continuation of the lower edge of the fabric side pieces 3 and 4. These pieces 3 and 4 are shown as joined to the outer edges 5 and 6 of the cups 1 and 2 respectively.

In order to effect complete encirclement of the body, a hook member 7 is shown carried by an

2

elastic tape 8. This tape passes through a slot formed by hook member 7; and the ends of tape 8 are appropriately attached to the side member 3.

A similar tape member 9 is attached to the side member 4 and carries a fastening means 10 having an eye 11 with which hook member 7 cooperates. A depending hook member 13 is also shown as supported by the fastening member 10 for attachment to the back portion of a garment, such as a skirt, or the like.

In the usual known type of brassière, the breast cups are joined together by a central portion intended to overlie the hollow between the breasts. Such a central portion, however, would be revealed when a low-cut evening gown is used.

In order to support the breast cups, without exposing any of the supporting elements, use is made of a rigid elongated member 14 that may be, for example, of a metal bar, and that has upwardly arched arms 15 and 16. The lower connecting portion 17 serves to join the two cups 1 and 2 at a point well below the hollow between the breasts. The arms 15 and 16 are located at the inner edges of the cups 1 and 2 and curve upwardly and outwardly to the upper edges of the respective cups. The contour of the member 14 corresponds to the base of the breasts. Furthermore, the member 14 is accommodated in a tubular sleeve or lining 18 that is sewn around the inner edges of the cups 1 and 2 and between the cups for the accommodation of the connecting member 17.

Furthermore, in order to reduce irritation of the skin, the inner side of this tubular member 18 is lined with a piled fabric 19, such as velvet. This fabric forms a thin strip corresponding in shape to the elongated member 14. A fabric web 20 is connected across the lower portions of the arms 15 and 16.

The connecting member 17 being disposed adjacent the lower edges of the breast cups 1 and 2, a low-cut evening gown may be worn without revealing any portion of the brassière. The hollow between the breasts is left uncovered for a considerable distance between the breasts. Furthermore, the elongated reinforcing member 14 is rigid enough to maintain the breast cups 1 and 2 in the supported position of Fig. 4.

In order further to support the brassière upon the body of the wearer, conventional shoulder straps 21 and 22 may be provided.

The inventor claims:

In a brassière, a pair of breast cups, an elongated rigid member of U-shaped configuration, the lower connecting portion of the member be-

ing disposed between the adjacent lower edges of the cups, and the arms of the member being curved to define those edges of the cups that are opposed to each other adjacent the center of the garment, said arms extending upwardly and away from the center of the garment to the top regions of the cups, and means for attaching the connecting portion and the arms to the cups.

JOSEPH R. BOWEN.
